UNITED STATES PATENT OFFICE.

WILLIAM NELSON COSGROVE AND GEORGE LUCIUS SMITH, OF FARIBAULT,
MINNESOTA.

CONCRETE CULVERT.

1,096,226.

Specification of Letters Patent. Patented May 12, 1914.

Application filed October 20, 1913. Serial No. 796,309.

To all whom it may concern:

Be it known that we, WILLIAM NELSON COSGROVE and GEORGE LUCIUS SMITH, citizens of the United States, residing at Faribault, in the county of Rice, State of Minnesota, have invented a new and useful Concrete Culvert, of which the following is a specification.

The present invention appertains to concrete culverts, and aims to provide a novel and improved cross culvert for streets or highways.

One of the objects of the present invention is to provide a culvert of the nature indicated, the bottom of which is adjustable, and the top of which is removable, in order to permit the culvert to be cleaned when necessary, and in order to permit the bottom to be adjusted between the sides according to the grade of the road, street or the like.

Another object of the present invention is to provide a unique top or cover construction for the culvert, which will permit of the expansion of the top or cover, without injurious effects.

It is also the object of the present invention to provide a culvert which may be embedded or planted in the road bed, in order that the top or cover of the culvert may form a crossing between the curbs or sides of the road or street, in alinement with the sidewalks.

It is also within the scope of the present invention to provide a concrete culvert which shall be comparatively simple, substantial and inexpensive in construction, and which shall be efficient in its use, as well as being capable of ready application to the road bed or the like.

With the foregoing general objects outlined, and with other objects in view, which will be apparent as the nature of the invention is better understood, the present invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:—

Figure 1 is a plan view of the culvert as

applied to a street, between the sidewalks, so as to form a crossing. Fig. 2 is an enlarged fragmental view of the culvert, portions shown in full, and portions being shown in section. Figs. 3, 4 and 5 are sectional views taken on the lines 3—3, 4—4 and 5—5 of Fig. 2, respectively.

In carrying out the present invention, there are provided concrete sides 1, which are preferably integral throughout the length of the conduit, and which may be reinforced, if desired. The sides 1 are connected by stay or separating bars 2, which have their ends bent angularly and anchored within the sides 1, adjoining the upper and lower edges of the sides. The lower stays 2 are preferably flush with the lower edges of the sides 1, while the upper stays 3 are spaced slightly below the upper edges of the sides, it being evident that the stays 2 will securely hold the sides in position with respect to each other. The bottom 3 is also constructed of concrete, and is preferably constructed of a number of sections placed end to end, the bottom having its upper surface concaved transversely, and a transversely concaved lining or flooring 4 being preferably placed upon the bottom 3. The bottom 3 is disposed snugly between the sides 1, and is free to be adjusted vertically between the sides, in order that the bottom may be placed at the proper slope desired, according to the grade of the road or street.

The top or cover embodies a plurality of sections 5 placed end to end, upon the sides 1, each of the sections 5 having a depending portion 6 intermediate its side edges and fitting between the upper edge portions of the sides 1 to lock the sections 5 against transverse movement with respect to the culvert, as a whole.

The end sections 5, and the sides 1 are provided with interengageable means for locking the end sections against sliding movements upon the sides, and to this end, tubular or pipe sections 7 are embedded within the end sections 5, and are designed to engage over dowels 8 engaged to the upper edges of the sides 1 adjoining the ends of the sides.

The adjoining ends of the cover or top sections 5 are spaced slightly apart, and the gaps or spaces between the ends of the sections 5 are closed by compressible packings 9 seated upon the sides, which are prefer-

ably of some fibrous material, such as soft wood or the like. The upper cross bars or stays 2 are preferably disposed directly below the joints between the cover sections 5 so as to assist in supporting the packing strips 9. The cover sections 5 are each provided with pipe sections or sockets 10 embedded within their side edges, to permit the cover sections to be lifted or raised by means of a 10 crow bar or other suitable implement.

In practice, the sides 1 of the culvert are placed within a cross ditch which is provided for the reception of the culvert, and the bottom 3 is then placed between the 15 sides and is adjusted to the required angle of inclination, the bottom being properly supported by a filling therein under. The cover sections may then be placed upon the sides, together with the packing strips 9, which 20 will complete the culvert.

The cover sections 5 are arranged to be flush with the surface of the road bed, and are preferably corrugated longitudinally of 25 the culvert, in order that the cover sections may serve as a crossing for pedestrians.

The fibrous packing strips 9 will permit the cover sections to expand and contract, without injurious effects, and without opening the culvert, the packing strips excluding 30 sand, dirt, and the like, due to traffic over the culvert. The present culvert will be safe under the traffic, and will serve as an effective conduit between the gutters along the sides of the road, as is obvious. It is evident

that the intermediate cover sections 5 are 35 free to slide longitudinally upon the sides 1, to permit the cover sections intermediate the end sections to adjust themselves as they expand and contract, the end cover sections being anchored to the sides to prevent their 40 displacement.

The cover sections 5 may be readily removed for cleaning out the culvert, and for readjusting the bottom, which may be necessary in grading the road. 45

Having thus described the invention, what is claimed as new is:—

1. A culvert embodying concrete sides, stays having their ends anchored to the sides along their upper and lower edges, a concrete bottom adjustably disposed between the sides above the lower stays, and a removable concrete top disposed upon the sides. 50

2. In a culvert, concrete sides, stay bars connecting the sides, a sectional concrete cover disposed upon the sides, and packing strips disposed between the cover sections, certain of the stay bars being disposed directly under the packing strips to support 55 the same. 60

In testimony that we claim the foregoing as our own, we have hereto affixed our signatures in the presence of two witnesses.

WILLIAM NELSON COSGROVE.
GEORGE LUCIUS SMITH.
